UNITED STATES PATENT OFFICE.

JOHN E. GLIDDEN, OF BEVERLY, MASSACHUSETTS, ASSIGNOR TO UNITED SHOE MACHINERY COMPANY, OF PATERSON, NEW JERSEY, A CORPORATION OF NEW JERSEY.

HEELING-MACHINE.

1,117,998.

Specification of Letters Patent. Patented Nov. 24, 1914.

Application filed December 4, 1908. Serial No. 466,022.

To all whom it may concern:

Be it known that I, JOHN E. GLIDDEN, a citizen of the United States, residing at Beverly, in the county of Essex and Commonwealth of Massachusetts, have invented certain Improvements in Heeling-Machines, of which the following description, in connection with the accompanying drawings, is a specification, like reference characters on 10 the drawings indicating like parts in the several figures.

This invention relates to heeling machines and more particularly to machines for attaching rubber top lifts or heels to boots 15 and shoes.

Where rubber top lifts or heels are attached to boots or shoes by nails or similar fastenings it is essential that the heads of the fastenings be embedded in the material 20 of the top lift or heel a considerable distance below the tread surface thereof. When a rubber top lift is to be attached to a leather heel by nails, the nails should be so driven as to penetrate the top lift and 25 heel, their points being clenched in the sole of the shoe and their heads buried in the top lift for a distance equal to substantially one half the thickness thereof. To secure these results in the most effective manner I pro- 30 vide a separate driver for each fastening to be driven, these drivers being mounted for reciprocation in suitable guideways, and being given positive nail driving movements the extent of which is just sufficient to em- 35 bed the heads of the nails the proper distance in the top lift. As illustrated herein, these drivers are in the form of plungers and are arranged to play in passages formed in the nail block head of a heel nailing ma- 40 chine of the type shown in United States Letters Patent No. 884,513, dated April 14, 1908, in which machine this invention is shown as embodied. In the machine shown and described in said patent, the nail block 45 head and driver head are mounted upon a die-bed spindle, which is reciprocated by suitable mechanism to cause the nail block to force the heel against the shoe, and, subsequently, through yielding connections be- 50 tween the nail block head and driver head, to move the driver head upwardly a farther distance, independently of the nail block head, whereby the drivers rise in the holes of the nail block and act upon the nails to 55 force them through the heel and into the

sole of the shoe. In said machine the heel and top lift holder is pivotally mounted above the nail block, and is locked in position with the heel over the nail holes therein during the heel attaching operation, but is 60 unlocked upon the descent of the nail block after the heel is attached, to permit the heel holder to be moved automatically out of position, and the top lift holder into position over the nail block, whereby, upon the 65 second rise of the nail block a top lift in said holder will be spanked upon the ends of the nails projecting from said heel. As hereinbefore stated, the plungers which are to act as drivers for the top lift fastenings, under 70 this invention, are arranged to play in passages formed in the nail block, and as herein shown these plungers have their nail-driving heads positioned to lie normally flush with the upper surface of said block, 75 and are at their opposite ends provided with yielding means applied thereto in such manner as to cause said ends to normally project a suitable distance below the lower surface of said block.

The driver head, carrying the usual drivers for the heel attaching nails, is preferably provided with suitable devices which are arranged to be projected to prevent said head from approaching the nail block sufficiently close to come in contact with the ends of the top lift attaching plungers upon the first, or heel attaching, actuation of the driver head, but are withdrawn to permit a nearer approach of the driver head thereto 80 upon its second actuation. As herein illustrated, said devices comprise spaced, sliding stops, of wedge form, having thereon inclined ribs to enter and move within similar grooves in the driver head. These stops 85 may be operatively connected with the heel and top lift carrier in such manner that when said carrier is moved to locate a heel over the nail block, the stops are projected, but when the said carrier moves to locate a 90 top lift over the nail block, the stops are withdrawn. This arrangement of top lift drivers and their operating mechanism in connection with a heel nailing machine of this type, whereby said drivers are rendered 95 inoperative during the heel attaching operation, but are rendered operative during the top lift attaching operation, I regard as an important feature of my invention.

The top lift attaching drivers, as before 110

stated, are shown as being slidably mounted in the nail block, and the number and arrangement of said drivers will be determined by the number and location of fastenings 5 desired for the top lifts. Such top lift drivers may be, and preferably are, arranged in suitable proximity to the heel nail drivers, and under one form of my invention some, or all, of the heel nail drivers may be 10 conveniently arranged for movement within passages which extend through the top lift drivers; but my invention is not to be considered as limited to this arrangement.

Other important features, including details of construction and combinations of parts, will be more fully hereinafter set forth and claimed.

Like reference characters denote like parts throughout the several views of the drawings.

Figure 1 is a perspective view of the principal parts of a heel nailing machine, having this invention applied thereto. Fig. 2 is a detail view, enlarged, showing the driver head and the movable stops for said head, in plan. Fig. 3 is a vertical sectional view through the driver head and nail block with a shoe thereon, on the line 4—4, Fig. 2, the parts being shown in the position they occupy during the heel attaching operation; Fig. 4 is a similar view showing the parts in the position they occupy during the top lift attaching operation. Fig. 5 is a perspective view of a leather heel with a rubber top lift 35 attached thereto, showing in a vertical section through the several layers the arrangement of the fastenings as applied by this invention.

Referring to Fig. 1, the frame 1, carries 40 the usual shoe supporting jack 2, which is mounted for movements into and out of position over the nail block 3. The nail block is carried by the nail block head 4, which has the depending rods 6, properly 45 spaced apart and serving to guide the driver head in its movements. The driver head 7 has the grooved collars 5 securely fastened thereto by the caps 6' bolted to the driver head, as shown, these collars serving as sliding 50 bearings to permit the movements of the driver head on the rods, and being, furthermore, provided with dependent guides 13 to sustain strong springs 14, to constitute a yielding means for holding the nail block 55 and driver head normally spaced apart. The driver head 7 has the usual supporting spindle, the same being raised and lowered by toggles actuated through a link, or other connection, from the main drive shaft, these 60 parts being under the control of a clutch, or equivalent device, which is preferably so constructed as to permit the nail block and driver head to be raised and lowered twice for every actuation of the clutch control 65 lever, said parts not being shown herein but

being shown and described in the patent above referred to.

The heel and top lift carrier 8 is preferably of substantially the same construction as that shown in the Letters Patent hereinbefore referred to, except that the supporting plate for the usual heel and top lift holding gages is not extended beneath the top lift gages to form a spanker, as such extension would interfere with the operation of the plungers 15 in driving fastenings through the top lift and heel. As disclosed in said Letters Patent, the carrier 8 is provided with the heel holding gages 8', 8², and the top lift holding gages 9', 9², and said carrier is pivotally mounted for movement over the nail block and has attached thereto suitable means, as the spring-actuated link 10, which acts with a normal tendency to oscillate the carrier in a direction to locate a top lift in the carrier in position over the nail block, the carrier being caused to move in the opposite direction to locate a heel therein over the nail block by the actuator 11 carried by the nail transerrer 12.

The parts so far described are all substantially shown and described in the aforesaid Letters Patent, and form no part of the present invention.

The top lift fastening drivers are herein shown in the form of plungers 15, each having at one end thereof the head 16, and at its opposite end a washer 18, or other equivalent means to sustain the pressure of a spiral spring 17. The plungers play in passages in the nail block, said passages being enlarged to form recesses at their upper extremities to receive the heads 16, and being recessed at their opposite extremities to accommodate the springs 17, said springs being normally held compressed between the shoulders formed by the ends of the recesses, and the washers 18. The plungers are longer than the thickness of the nail block, and are normally held by the springs with their heads 16 within the upper recesses and their extremities flush with the upper surface of the block, while their opposite ends project a slight distance beyond the lower surface of the block, as shown in Fig. 3. As shown in dotted lines in Figs. 3 and 4 of the drawings, the plungers may be longitudinally bored to receive the usual heel nail drivers 7', some of which drivers I have shown as telescopically mounted in the plungers; but while I prefer this arrangement, my invention contemplates the employment of any other form of plunger.

The stops 19 are, as here shown, of wedge form, and each has an upper edge lying normally in a horizontal plane, and a lower edge inclined thereto, the latter preferably being provided with a guiding rib 19'.

As shown in Fig. 1, the driver head 7 has formed therein two guideways or grooves

located, respectively, upon opposite sides of the drivers 7', and these grooves are inclined to correspond with the inclination of the ribs 19', which slide therein. A bracket 20 is shown as clamped to the stops at their rear ends by winged nuts 21, which engage threaded extensions on the stops, the extensions passing through slots in said bracket, as shown in Fig. 2, whereby to permit 10 adjustments to accommodate variations in the lateral spacing of the stops. The bracket is, furthermore, provided with an arm 22 having a slot therein to be engaged by a crank 23, mounted on a rod 24, said 15 rod being operatively connected to the heel and top lift holder 8, so as to turn therewith. The crank 23, as shown, is elongated in the direction of the axis of the crank shaft whereby the bracket 22 may slide 20 along the crank as the driver head reciprocates and is thus maintained in operative engagement with the crank in all positions of said head.

The machine is ready for operation when 25 all of the parts occupy the positions shown in Figs. 1, 2 and 3 of the drawings, that is, after the transerrer 12 has, through the actuator 11, moved the heel holder to heel attaching position, and has deposited the 30 requisite number of nails in the nail passages of the nail block, and a heel blank has been placed in the heel holder, and a rubber top lift loaded with nails has been placed in the top lift holder. The crank 23, 35 bracket 20 and stops 19 are now as shown in full lines in Fig. 2, the stops being projected to lie with their upper edges in a plane above the plane of the upper surface of the driver head. The clutch controlling 40 lever being actuated, the nail block and driver head rise, and the heel is first forced against the shoe on the jack by the pressure imparted thereto from the nail block, the springs 14 being thereafter compressed, 45 whereby the driver head approaches the nail block and the drivers 7' act to drive the nails through the heel and into the sole of the shoe. Owing to the position of the stops 19, at this time, however, the driver 50 head is not permitted to approach the nail block sufficiently to come in contact with and actuate the plungers 15. The nail block then descends, thereby actuating the trip device to release the heel and top lift carrier, and permit the spring-actuated link 55 10 to move the top lift carrier into position over the nail block, this movement also serving to turn the rod 24 and thereby the crank 23, and to shift the stops 19 to the 60 position shown in dotted lines in Fig. 2 and in full lines in Fig. 4, with their edges lying flush with the upper surface of the driver head. The nail block and driver head then 65 rise for the second time, and the top lift is first forced against the heel by the nail

block, and thereafter upon the continued upward movement of the driver head, the plungers 15 are actuated to force the fastenings *a*, having thereon the washers *b*, through the heel and into the sole of the shoe, the plungers being by such operation projected above the upper surface of the nail block a sufficient distance to embed the heads of the fastenings carrying the washers into the material of the top lift, as 70 shown in Fig. 5. The nail block and driver head then descend, permitting the springs 17 to retract the plungers 15 into the nail block so that their heads 16 lie flush with the upper surface thereof, and the parts of 75 the machine again assume the positions shown in Fig. 1, and are thereby in readiness to repeat their cycle of operations.

Having thus described my invention, and having also described one type of machine 80 within which it may be conveniently embodied, but without limiting myself to this particular embodiment of the invention, nor to the details of construction described other than as defined in the following 85 claims, what I claim and desire to secure by Letters Patent of the United States is:—

1. In a machine of the class described, the combination with a shoe support, of a driver support, drivers movably sustained in 90 said driver support and actuating means for the drivers constructed and arranged to drive fastenings into a heel or top lift so as to sink the heads of such fastenings below the surface of the work.

2. In a machine of the class described, the combination with a shoe support, of a driver support, a complete set of independent drivers movably sustained therein at all 95 times and means to actuate said drivers constructed and arranged to embed uniformly the heads of a group of fastenings in a heel or top lift while attaching such heel or top lift to a shoe.

3. In a machine of the class described, a 100 driver support, drivers mounted to reciprocate therein, means to actuate the drivers to embed the heads of fastenings below the surface of the material of a top lift or heel, and yielding means within the driver support to return said drivers to inoperative 105 position.

4. In a machine of the class described, the combination with a driver support having passages therethrough, said passages 110 terminating in recesses at the upper and lower surfaces of the support, of drivers in said passages provided with heads fitting the upper recesses, springs surrounding said drivers and occupying the lower recesses and retaining means for the springs located on said drivers.

5. In a machine of the class described, the combination with a nail block, of plungers supported by said nail block and ar- 115 120 125 130

ranged longitudinally for movement therein, and a driver head movable relatively to said nail block and arranged to actuate said plungers to drive fastenings and to embed 5 their heads below the surface of the material of a heel or top lift.

6. In a machine of the class described, the combination with a nail block having 10 plungers movably supported in parallel relation thereby, said plungers being of a length exceeding the thickness of the nail block, of a driver head movable relatively to said nail block and periodically into and out of engagement with the plungers, the 15 head being arranged to actuate said plungers.

7. In a machine of the class described, the combination with a nail block having 20 plungers movably supported therein, said plungers being of a length exceeding the thickness of the nail block, and being normally maintained with their ends approximately flush with the work engaging surface of said block, of a driver head movable 25 relatively to said nail block and said plungers.

8. In a heel attaching machine, the combination with a nail block having top lift attaching 30 plungers movably supported therein, of a driver head movable toward and from said plungers, means for imparting heel and top lift attaching movements to said head, and means to prevent the driver head from acting upon the plungers 35 during the heel attaching movements.

9. In a heel attaching machine, the combination with a nail block having plungers movable therein and arranged to extend beyond 40 said block, of a driver head movable toward and from said plungers, means for imparting heel and top lift attaching movements to said head, and means to prevent the driver head from acting upon the plungers 45 during the heel attaching movements of the driver head.

10. In a heel attaching machine, the combination with a nail block having top lift attaching 50 plungers retained therein and heel attaching driver passages therein, of a driver head carrying drivers to move in said passages and arranged for movements relatively to the nail block and said plungers, means for imparting heel and top lift attaching movements to said head and 55 means to prevent the head from actuating said plungers during the heel attaching movements.

11. In a heel attaching machine, the combination with a heel and top lift carrier, of 60 a nail block having plungers movably retained therein and arranged to extend beyond said block, a driver head movable relatively to said block and plungers and also to actuate the plungers, and means operating 65 to prevent the head from actuating the

plungers when a heel is in attaching position but to permit actuation of the plungers when a top lift is in attaching position.

12. In a heel attaching machine, the combination with a heel and top lift carrier, of 70 a nail block having plungers movably retained therein and arranged to extend beyond said block, a driver head movable relatively to said block and said plungers, and means carried by said driver head constructed to prevent the head from actuating the plungers when the heel is in attaching position, but to permit actuation of the plungers when a top lift is in attaching 75 position.

13. In a heel attaching machine, the combination with a heel and top lift carrier, of 80 a nail block having plungers movable therein and arranged to extend beyond said block, a driver head movable relatively to 85 said block and plungers and also to actuate the plungers, and a movable stop carried by said driver head and arranged to be positioned to prevent the driver head from actuating the plungers when a heel is in attaching position but to permit actuation of the plungers when a top lift is in attaching 90 position, said stop being operated from the heel and top lift carrier.

14. In a heel attaching machine, the combination with a heel and top lift carrier, of 95 a nail block having plungers movable therein, and arranged to extend beyond said block, a driver head movable relatively to said block and arranged to actuate said 100 plungers, spaced stops carried movably in said driver head to control its movements relatively to the plungers, a bracket adjustably secured to said stops and provided with an arm, and a crank in slidably engagement with said arm and operatively connected with the heel and top lift carrier.

15. In a machine of the class described, the combination with a support, of top lift 105 attaching plungers movable therein, and drivers arranged telescopically within said plungers.

16. The combination with a nail block having passages and top lift attaching 110 plungers in said passages, of a driver head having drivers telescopically arranged within said plungers.

17. The combination with a nail block having passages and top lift attaching 115 plungers in said passages, of a driver head having drivers telescopically arranged in said plungers, said driver head being arranged to actuate said plungers.

18. The combination with a nail block having passages and top lift attaching 120 plungers in said passages, and extending beyond said nail block, of a driver head having drivers telescopically arranged within said passages, the driver head being adapted to actuate said plungers. 125

19. In a machine of the class described, a driver support, fastening drivers retained by the support and arranged to reciprocate therein, means to project the drivers beyond the support to cause them to drive fastenings into a heel or top lift so as to embed the heads of such fastenings below the surface of the stock, and means to withdraw the drivers within said support.
20. In a machine of the class described, a driver support, fastening drivers retained by the support and arranged to reciprocate therein, means to project the drivers beyond the support to cause them to drive fastenings into a heel or top lift so as to embed the heads of such fastenings below the surface of the stock, and yielding means to withdraw the drivers within said support.
21. In a machine of the class described, the combination with a driver support, of drivers movably mounted in said support and arranged to be projected beyond the surface thereof, and a driver head movable relatively to said drivers preliminarily to the driving operation and, in the same continuous movement arranged to actuate the drivers to drive fastenings into a heel or top lift.
22. In a machine of the class described, the combination with a driver support, of drivers movably mounted therein, said drivers being of greater length than the thickness of the support, and a driver head movable relatively to said drivers preliminarily to the driving operation and, in the same continuous movement, arranged to actuate the drivers to drive fastenings into a heel or top lift.
23. In a machine of the class described,
- the combination with a driver support, of heel-attaching and top lift-attaching drivers movable therein, a driver head, and means for varying the relative positions of the driver support and driver head on alternate reciprocations and to first actuate the heel-attaching drivers and to thereafter actuate the top lift-attaching drivers.
24. In a machine of the class described, the combination with a heel and top lift carrier, of a nail block having plungers movable therein and arranged to extend beyond the block, a driver head movable relatively to said block to actuate said plungers, and means for varying the relative positions of the nail block and the driver head in successive driving operations and arranged to prevent the actuation of the plungers when a heel is in attaching position but to permit actuation of the plungers when a top lift is in attaching position.
25. In a machine of the class described, the combination with a block having plungers movably supported therein, said plungers being of a length exceeding the thickness of the block, and being normally maintained with their driving ends rigidly supported in position flush with the acting surface of the block, of a second block movable to engage the opposite ends of said plungers and project them without the surface of said supporting block.

In testimony whereof I have signed my name to this specification in the presence of two subscribing witnesses.

JOHN E. GLIDDEN.

Corrections in Letters Patent No. 1,117,998.

It is hereby certified that in Letters Patent No. 1,117,998, granted November 24, 1914, upon the application of John E. Glidden, of Beverly, Massachusetts, for an improvement in "Heeling-Machines," errors appear in the printed specification requiring correction as follows: Page 3, line 130, after the word "supported," insert the word *longitudinally*; page 4, line 1, strike out the word "longitudinally"; and that the said Letters Patent should be read with these corrections therein that the same may conform to the record of the case in the Patent Office.

Signed and sealed this 2nd day of February, A. D., 1915.

[SEAL.]

R. F. WHITEHEAD,
Acting Commissioner of Patents.
